UNITED STATES PATENT OFFICE

WALTER S. PFEIFER, OF MILWAUKEE, WISCONSIN

DRIER

Application filed October 26, 1927. Serial No. 228,783.

This invention relates to certain new and useful improvements in driers of the type especially designed for use in public lavatories, factory wash rooms and the like, thus obviating the necessity of towels, and has as an object the provision of a machine of the character described in which the velocity of drying air is properly proportioned to the temperature of the air so as to insure the rapid drying of the user's hands without any discomfort.

Heretofore devices of this character have been controlled by a hand operated switch, which is objectionable in that the operating lever or switch becomes a carrier of disease germs, especially as it must be manipulated with wet hands.

With the above and other objectionable features in mind, this invention has as one of its objects the provision of a very durable and practical drier, the switch of which is operated by a foot pedal which holds the switch in operative position only during the period the pedal is depressed and which is so constructed and designed as to be capable of withstanding all the abuses to which a machine used by the general public is subjected.

Another object of this invention resides in the provision of an improved drier of the character described, which will very efficiently and quickly dry a person's hands, and which has means for readily adjusting the speed of its motor and consequently the velocity of the blast.

Another object of this invention resides in the provision of an improved heating element which is so designed and arranged that the incoming air is instantly heated to a desired degree with a minimum current consumption and which is so arranged as to prevent any possible injury to users and also any possible damage to the machine by its careless use.

It is another object of this invention to provide an improved drier of the character described in which the useful area of the heating element is capable of ready adjustment to permit the regulation of the drier to suit any particular installation.

Another object of this invention resides in the provision of a machine of the character described which is so designed that water falling into the blast outlet when the device is inoperative will not touch any vital spot and is instantly drained therefrom.

Another object of this invention resides in the provision of a device of the character described having a substantially one piece hood encasing the operating parts to thoroughly protect the same against entrance of foreign matter and having an opening in its under surface through which the air enters for the blower, the air cooling the motor to prevent over heating in its passage to the heating element.

A further object of this invention resides in the provision of an improved device of the character described having a vertical standard or support with a flange or flare at its upper end over which an enclosing hood or housing surrounding the operating mechanism fits with its lower marginal edges extending therebeyond and slightly spaced therefrom to provide an air inlet through which the air is supplied to the drier.

And a still further object of this invention resides in the provision of an improved switch structure for a device of the character described which is so designed and constructed as to require a minimum of movement and which will be extremely durable.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a view, partly in elevation and

partly in section, of a drier embodying my invention;

Figure 2 is a view, partly in top plan and partly in section, and taken through Figure 1 on the plane of the line 2—2.

Figure 3 is a transverse sectional view taken through Figure 1 on the plane of the line 3—3;

Figure 4 is a fragmentary view, partly in top plan and partly in section, illustrating the manner of mounting the movable switch lever;

Figure 5 is a detail view, partly in section and partly in elevation, of the treadle actuated means and its connection with the switch lever;

Figure 6 is a perspective view of the improved heating element detached, parts thereof being broken away to illustrate structural details;

Figure 7 is a fragmentary perspective view of the marginal edge portion of the top of the heater casing;

Figure 8 is a fragmentary detail view, partly in section and partly in elevation, illustrating one of the heating element mounting members;

Figure 9 is a diagrammatic view illustrating the wiring diagram when the device is used with 110 volts, and

Figure 10 is a view similar to Figure 9 illustrating the wiring diagram when the device is used in connection with 220 volts.

Referring now more particularly to the accompanying drawings in which like numerals designate like parts throughout the several views, the numeral 5 designates a hollow pedestal or standard having a flared base 6 adapted to be bolted or otherwise fixed to a floor and a flared top 7 of substantially rectangular shape and providing a flange over which a housing or casing 8 is secured.

Mounted on the flange top of the pedestal is a bed plate or base 9, to which a motor 10 is secured by screws or other means 11, the plate 9 having a well 12 parallel with the motor axis and into which oil conveying tubes 13 having wicks therein extend from the bearings of the motor so that a relatively large amount of lubricant may be supplied through a filling spout or other means 14. The shaft 15 of the motor extends into a blower 16 consisting of a casing 17 having a tangentially and vertically disposed outlet duct 18 and a central air inlet 19, see Figure 3, in its side opposite the motor. The blower 16 is rigidly mounted on a plate 20 secured to the side of the casing 17 opposite its air inlet by screws or other means 21, and the plate is fixed to the base 9 by screws 22.

An annular flange 23 surrounds the air inlet opening 19 and is flattened at diametrically opposed points to fit within the rectangular shaped housing of a heating unit 24, to be later described, which is secured to

the flange by screws or other means 25. The plate 9 does not extend entirely across the flange 7 and has a reduced projection 26 at its inner end from which a line conduit 27 and the switch operating mechanism, to be later described, are supported.

The heating unit 24 is secured within an open ended housing, formed by top and bottom walls 28 and 29, respectively, and side walls 30 and 31, the walls 28 and 29 having slots or recesses 32 communicating with their side edges and to be closed at their outer ends by flanges 33 on the marginal edges of the side walls and directed over the edges of the walls 28 and 29 and there secured by screws or bolts 34 to secure the housing together. The heating element 35 is preferably of a continuous length supported at spaced points from staggered bushings 36 carried by the top and bottom walls, the center portion of the element being secured to a bushing 37 engaged in a slot 38 in one end of the top wall and there secured by cement or other means 39 and its ends being secured to bushings 40 mounted in slots 41 in the opposite end of the bottom wall and there secured by curling that portion of the metal between the slots 41, as at 42, see Figure 6.

The element bushings are of approximately spool shape, having a central groove or channel 43 of a width to receive either the top or bottom walls and the bushings 36 are secured in place by the flanges 33 of the side walls closing the outer ends of the slots 32. The bushings also are provided with central bores 44 which communicate with recesses or counterbores 45 in the heads thereof and through which terminal or element mounting studs 46 pass, the intermediate bushings having insulating cement or other means 47 filling the recesses over the heads of the mounting studs 46 and the bushings 37 and 40 having threaded terminals 48 extended therefrom, as best shown in Figure 6. The bushings 36 nearest the bushing 37 likewise have terminal studs 49 extended therefrom, for the purpose later described.

An insulating panel 50 is supported from one side wall of the heating unit and terminals 51 and 52 are fixed to the panel and have outside service lines 53 connected therewith. The terminal 51 is connected with one side of a suitable switch mechanism 54, to be later described, by a conductor 55 and the other side of the switch structure is connected with the ends of the heating element by a common conductor 56, the terminal 48 connected with the center of the heating element being connected with the other side of the line by conductors 57 and 58 leading to the terminal 52. When the outside service voltage is 110, the motor is parallel with the heating element having one side connected with the conductor 56 by a conductor 59 and its other side connected with the terminal 52

through a conductor 60, and the conductor 58. However, assuming that the service voltage is 220, both parts of heating element are in series and the motor is in parallel with one part, the terminal 48 connected with the center of the element being connected with one side of the motor by a conductor 61, and the other side of the motor being connected with the terminal 52 through a conductor 62.

10 The switch mechanism 54 consists of a tube 63 having contacts 64 and 65 extended thereinto and adapted to be bridged by a movable contactor 66 such as mercury, the tube being detachably mounted on a lever 67 by spring clips or other means 68. The lever 67 is medially pivoted to the projection 26 of the plate 9 by a screw or other means 69, the axis of which passes through the center of gravity of the mercury tube 63, and one 20 end of the lever 67 has a counter-balance 70 thereon and the other end an angular piece 71 with which the upper end of an operating rod 72 is connected, in the manner to be later described. A treadle 73 pivotally mounted 25 at the base of the pedestal is connected with the rod 72 so that depressing of the treadle moves lever 67 on its pivot to swing the tube 63 to a position where the contactor 66 bridges the contacts 64 and 65 to establish 30 the circuits of the heating element and motor.

As the pivot 69 of the lever 67 passes through the center of gravity of the mercury tube it will be readily apparent that only a small movement of the treadle is necessary to actuate the switch mechanism and as a result rapid and continued actuation of the treadle will not be injurious to the tube as the inertia of the mercury will retain the switch in one 40 position during such abuse.

The rod 72 and the treadle 73 are normally urged to their inoperative positions by an expansile spring 74, held in compression between an arm 75 and a nut 79 threaded on the rod, suitable cups 80 providing seats for the ends of the spring. The arm 75 is supported from the projection 26 by bolts or other means 76 passed therethrough and through 50 spacing sleeves 77 and 78, and a second arm 81 is secured in alignment with the arm 75 between the spacing members, nuts threaded on the lower ends of the bolts 76 firmly holding the arms and spacing members in position.

The arm 81 forms a stop limiting upward movement of the rod 72 under influence of the spring 74, the nut 79 abutting thereagainst. The rod 72 extends upwardly 60 through the arm 81 and is freely slidably passed through an opening in the horizontal portion 82 of the angular member 71, and has an expansile spring 83 coiled about its upper end, the spring being confined between the 65 portion 82 and a cup 84 held in place by a

nut 85 threaded on the extreme upper end of the rod.

To operate the drier, the user actuates the treadle to tilt the mercury contactor to its contact making position thus completing 70 the circuit for the motor and the heating element. It will be noted that the movement of the rod 72 caused by the actuation of the treadle is transmitted to the lever 67 through the spring 83, absorbing the direct shock 75 of the downward movement, which very often is a severe blow, and preventing injury to the switch, the lever 67 moving downwardly until the latter portion 82 of the angular member 71 carried thereby engages the arm 81 and further movement of the rod merely compresses the springs 74 and 83.

The unopposed upward movement of the rod 72 in the lateral portion 82 of the member 71, when the pressure on the treadle is released, permits the springs to snap the rod up without carrying the switch lever with it, which is returned to its open position by the counter balance 70, the spring 83 cushioning its return.

It is often desirable that the speed of the blower motor be reduced, and when the drier is operated on a voltage of 110 this is done by disconnecting the conductor 60 from the conductor 58 and connecting it to any desired contact stud 49, as shown by the dotted lines 60' in Figure 9. It will be apparent that when the stud 49 farthest from the contact 48 is used, the motor speed will be the minimum which the adjustment permits, it is also obvious that the contacts 49 on either side of the heater element may be used.

When the service voltage is 220, the reduction of the motor speed is affected by disconnecting the conductor 61 from contact 48 and connecting it with any of the lower contacts 49 (see Figure 10) as shown by dotted lines 61', the desired degree of reduction governing the selection of the contact 49 with which the motor lead is connected. Connecting the motor lead 61 with any of the upper contact studs 49, in Figure 10, increases the speed, as will be readily apparent.

Means are also provided to increase the intensity of the heat produced by the element, which is accomplished by shortening the length of the element by connecting two opposite contact studs in the manner shown by the dotted lines 57' in Figure 9.

As long as the treadle is held down the circuits remain closed, the air entering the hood or case 8 through the space which extends around its lower periphery, being heated as it passes through the heating element to the inlet of the blower, and being expelled in the usual manner at a velocity which is readily governable, as has been described.

What I claim as my invention is:

1. In an appliance of the character described, a supporting base, drying mecha-

nism mounted on the base and including a blower having an air inlet and outlet, a housing entirely enclosing the drying mechanism, the housing having an opening with which the air outlet registers, and an air inlet passage between the adjacent edges of the housing and base and through which air enters the interior of the housing to the blower.

2. In an appliance of the character described, a supporting base, drying mechanism mounted on the base and including a blower having an air inlet and outlet, a housing entirely enclosing the drying mechanism, the housing having an opening with which the air outlet registers, an air passage between the adjacent edges of the housing and base and through which air enters the interior of the housing to the blower, and means for heating the air expelled through the blower outlet.

3. In an appliance of the character described, a supporting base, drying mechanism mounted on the base and including a blower having an air inlet and outlet, a housing entirely enclosing the drying mechanism and having an opening with which the air outlet registers, an air passage between the adjacent edges of the housing and base and through which air enters the interior of the housing to the blower, an open ended member communicating with the blower inlet, and means within said member for heating the air passing therethrough to the blower.

4. In an appliance of the character described, a supporting base, drying mechanism mounted on the base and including a blower having an air inlet and outlet, a housing entirely enclosing the drying mechanism and having an opening with which the air outlet registers, an air passage between the adjacent edges of the housing and base and through which air for the blower enters the interior of the housing, an open ended member communicating with the blower inlet, means within said member for heating the air passing therethrough to the blower, a motor for operating the blower, and means for controlling said motor speed.

5. A device of the character described, comprising a pedestal, a base plate on the upper end of the pedestal, a drying mechanism mounted on the base plate above the pedestal and including a motor, a blower driven thereby having an air inlet and an air outlet and a heating element for air impelled by the blower, a housing supported from the pedestal and entirely enclosing the drying mechanism and with said pedestal imparting a neat exterior appearance to the device, means for supplying air to the blower inlet, and an air outlet carried by the casing and with which the blower outlet registers.

In testimony whereof I have hereunto affixed my signature.

65 WALTER S. PFEIFER.
